United States Patent Office.

JACOB HETZEL AND SAMUEL H. HAGER, OF MIAMISBURG, OHIO.

Letters Patent No. 86,669, dated February 9, 1869.

IMPROVED MEAT-CUTTER.

The Schedule referred to in these Letters Patent and making part of the same.

To all whom it may concern:

Be it known that we, JACOB HETZEL, of Miamisburg, in the county of Montgomery, and State of Ohio, and SAMUEL H. HAGER, of Miamisburg, in the county of Montgomery, and State of Ohio, have invented a new and useful Improvement in Sausage and Bologna-Cutters; and we do hereby declare that the following is a full and exact description of the same, reference being had to the accompanying drawings, and to the letters of reference marked thereon.

This invention consists in a simple and efficient device for chopping meat into small particles, for the manufacture of sausage, &c., and to this end, a series of knives is employed, which are operated by cams on a revolving cylinder, as well as by a series of C or other-shaped springs; also, a revolving cylinder, or bed-plate, for the efficient operation of the machine, as will hereinafter more fully appear.

In the drawings—

A A' A' A'' A'' represent uprights, which constitute the main part of the frame-work.

Within the area described by the posts A A' A', and near the base of the same, is a circular block B, of wood, or other suitable material, which constitutes the surface upon which the knives operate.

It is provided with an annular rim, b, on its upper edge, which projects upward sufficiently far to form a reservoir or receptacle for the meat, and on its lower edge, with cogs, c c, &c., which mesh with the screw C on shaft E, upon one end of which is the pulley E'.

It should be here stated that the block B is pivoted on the vertical shaft e, and admits of a rotary motion by means of the cogs c c, &c., and screw C.

A friction-roller, e', is placed beneath the block B, to facilitate its revolution.

Directly above block B, and working in sockets on beams A³ A³, is the cylinder F, which is provided, at one end, with a hand-wheel, or pulley, f, and at the other, with a pulley, f'.

Upon the surface of the cylinder F are arranged three spiral rows of teeth, or projections, g g, &c., the upper sides of which present plane surfaces, the lower sides being bevelled off, as shown.

In the construction of this cylinder lies one of the most important features of our invention. The usual construction, when a metallic axle is employed, is to run it directly through the centre of the cylinder, thereby employing a single shaft. Our method, however, differs essentially from this. We construct one cylinder, of solid wood, or other suitable material, to each end of which we attach, by screws, the caps, or flanges, G G, on which are cast the axles g' g', thus constructing both flange and axle in one piece.

H H, &c., represent arms, which are pivoted to the rod h between the uprights A'', and may vary in number, as required.

The free end of each arm is provided with a slot, i, through which passes the upright rod I of the stamper I', which is pivoted therein at i'.

To the under surfaces of the arms H are attached, by means of staples, j, the connecting-rods J, which communicate with the springs K, and enable the same to perform their function, which is to cause the knives

or stampers, to descend with a greater degree of force.

The knives, or stampers, I', are constructed of different widths, those occupying the central position having the longest blades, while, towards either end, they decrease in length in such a degree that their outer edges shall form an arc corresponding to the curvature of the rim b of the block B.

Between the uprights A' A' is the cross-beam L, to which is attached the guide-plate L, which is provided, at its upper and lower edges, with slotted flanges, l l, having slots, corresponding, in number and size, to the rods I, and, at its lower edge, with two grooved projections, m m, in which fits the guide-bar m', secured by the pins n n. By this arrangement, the knives, or stampers, are held in position.

The rods I are provided with holes, o o, &c., by means of which the knives may be lowered as the surface of the block B becomes worn away.

The operation of our machine is as follows:

Let either hand or other power be applied to the wheel f, which is connected by the belting P with the pulley E'. This will effect the revolution of the screw-shaft E, and by its connection with the cogs c of the block B, cause the same to revolve slowly. At the same time, the teeth, or projections g, engage with the free ends of the arms H in such manner as to cause the knives to fall in regular succession, the bevelled edges of the teeth insuring a prompt release of the knives at the moment they have attained a sufficient elevation. Meanwhile, the constant revolution of the block, by means of the above-mentioned mechanism, brings every part of the surface under the action of the knives, thereby insuring their efficient action on all parts of the block.

The advantages appertaining to our invention are cheapness, simplicity, ease of construction and attachment, and effectiveness, the construction of the axles being one of great cheapness and simplicity, avoiding the necessity of boring through the cylinder, as is usually done.

The guide-bar m' is also of great advantage, rendering it almost impossible for the knives to get out of place, its simplicity and strength rendering it exceedingly effective.

Having thus fully described our invention,

What we claim, and desire to secure by Letters Patent, is—

1. In a sausage-cutter, the guide-plate L, consisting of the slotted flanges l, grooved projections m m, and guide-bar m', as and for the purpose set forth.

2. The sausage-cutter above described consists of the block B, with the cogs c c, screw C, shaft E, and pulley E', cylinder F, with teeth g, flanges G G, and axles g' g', arms H H, rods I of knives I', guide-plate L, and springs K, all arranged and operating substantially as described.

This specification signed and witnessed, this 14th day of December, 1868.

JACOB HETZEL.
